United States Patent Office

Des. 194,516
Patented Feb. 5, 1963

194,516

SELF-POWERED VARIABLE FLUID PROPOR- TIONER OR SIMILAR ARTICLE

Nat Cordis, Crown Farm, Silver Lake, Wis.

Filed Nov. 9, 1961, Ser. No. 67,447

Term of patent 14 years

(Cl. D65—1)

Fig. 1.

FIGURE 1 is a top perspective view of a self-powered variable fluid proportioner or similar article showing my new design;

FIGURE 2 is a top perspective view thereof taken from the other side and end; and

FIGURE 3 is a top plan view thereof.

I claim:

The ornamental design for a self-powered variable fluid proportioner or similar article, as shown.
